UNITED STATES PATENT OFFICE.

WILLIAM C. LOUDON, OF ST. LOUIS, MISSOURI.

GAS-GENERATING FURNACE.

1,145,327.

Specification of Letters Patent.

Patented July 6, 1915.

Application filed September 28, 1912. Serial No. 722,981.

To all whom it may concern:

Be it known that I, WILLIAM C. LOUDON, a citizen of the United States, and resident of St. Louis, Missouri, have invented certain new and useful Improvements in Gas-Generating Furnaces, of which the following is a specification.

This invention relates to improvements in gas generating furnaces constructed of the coal gas type and has for its object an air circulating medium by which the air is primarily heated before being mixed with the heat and gas directed from the furnace so as to deliver around each gas retort a uniform heat and a means for regulating the circulation so as to keep the heat around the retorts at an even temperature.

A further object of my invention is to construct a furnace which is commercially termed a bench of nines and suitable passages arranged within the structure through which air is admitted from the bottom and is circulated in such manner as to be primarily heated before entering the combustion chamber from which the heat is directed against all of the gas retorts.

A further object is to construct a particular form of passage through which the air must circulate before entering the combustion chamber and said air while circulating through these passages is heated to a higher degree than is now accomplished by the present form of gas furnaces and to obtain a greater heating efficiency with a small amount of fuel.

Figure 1 is a cross sectional view taken on the line 1—1 of Fig. 3. Fig. 2 is a longitudinal sectional view taken on the line 2—2 of Fig. 1. Fig. 3 is a horizontal sectional view taken on the line 3—3 of Fig. 1. Fig. 4 is a detail vertical sectional view taken on the line 4—4 of Fig. 3. Fig. 5 is a horizontal combination sectional view taken on the line 5—5 of Fig. 1. Figs. 6, 7, 8, and 9 are detail perspective views of several of the tiles made use of in constructing my improved furnace and for forming the necessary passages.

In the construction of my invention I provide a gas generator composed of a pair of side walls 10 and 11 connected together by an arch 12, a front wall 13 and a rear wall 14.

In the body of the generator is located a suitable furnace provided with a fire-box 15 in which is located the usual grate bars 16

on which the fuel is located; the upper portion of the fire-box or furnace is arched as indicated by the numeral 17 and at intervals along the top are located nostrils 18; through these nostrils 18 which are the only outlets and through which the products of combustion pass out into the upper portion of the generator to mingle with and mix with a supply of primarily heated air.

Air is fed to the furnace so as to provide the proper draft through the air passages 19, which extend from the front of the structure running rearwardly the depth of the furnace communicating with a cross port 20 and from thence the air passes forwardly through the air passage 21 and is discharged under the grate bars through the openings 22; this method of circulating the air beneath the grate bars, primarily heats the same to a proper degree so as not to chill the fire and interrupt the proper combustion.

On each side of the furnace and built in the structure are flue tiles 23 forming suitable passages through which the unused particles of combustion travel on their way out to the stack; the position of these tiles is such as to provide air passages through which the air passes to be primarily heated by the flues before intermingling with the gases and products of combustion delivered from the furnace.

The structure on both sides of the fire box or furnace being identical, the description of one will suffice. The structure of the flue tiles and the air passages formed thereby is as follows: The tiles 23 forming the flues are arranged in a tier and extend horizontally as shown in Figs. 2, 3, and 4 and are joined together by suitable tile or brick work as indicated by the numeral 24 forming on each side thereof air passages 25 and 26. These air passages 25 and 26 are divided into ports 27 and separated from each other by the elongated division tiles 28; these ports into which the air passages are divided are clearly shown in the sectional view, Fig. 4; the air is admitted through the openings 29 and 30 located in the front and at the base of the structure and is permitted to pass upwardly through the passages 31 and 32 to the top or cover 33; from these passages the air passes downwardly through the ports 27 in a direction indicated by the arrows 110 (see Fig. 4) and the circulation from each of the passages 31 and 32 is separated by

the partition 34, the air passing downwardly through these various ports then passing to the opposite side through the ports 35 located beneath the lowest flue tile; this air is then directed upwardly through the ports 36 located on the opposite side of the flue tiles and enters into the combustion chamber 37 by way of the inlet ports 38 located at intervals throughout the length 10 of said chamber. This air after having been excessively heated by its circulation around the flue tiles and mixed with the products of combustion in the combustion chamber utilizes all of the heat products and permits 15 the heat to pass upwardly contacting with the several gas retorts 39.

Over the chamber 37 is located a plurality of tiles 40 spaced at intervals apart forming direct passage-ways 41 (see Fig. 2) 20 and direct communication from the chamber 37 to the passage 42 is prevented by a solid wall of tiles 43, the construction of which is clearly shown in detail in Fig. 9; this structure of tile serving as a deflector as well as 25 support for the lowest row of retorts. These tiles are supported on blocks 44 shown in detail in Fig. 8 having a flared depression 45 which forms the upper portion of the inlets 38; these blocks in turn are supported on 30 tiles 46 shown in detail in Fig. 6 and each of these blocks is recessed as indicated by the numeral 47 which communicates with the depression 45 completing the series of passage ways 38; the several tiles are keyed together by the wedged tiles 48, their ends supported in the recess 49. The edges of the tiles 46 are tongued and grooved as shown 35 so that when the tiles are laid they form a complete leak proof partition. Back of this 40 series of tiles is the chamber 42 through which the heat after having contacted with the several retorts passes on its way out toward the stack; this chamber has communication with the passages 50 and 51, the heat 45 passing downwardly through both of these passages in a direction as indicated by the arrows (see Fig. 2) passing alternately from one of the flues formed by the flue tiles 23 to the other until it reaches the bottom-most 50 flue then it passes out into the flues 52 and is led to the stack 53. On the top of the passages 50 and 51 are located dampers 54 which can be manipulated by inserting an instrument through the opening 55 after 55 first removing the plugs 56, and by the regulation of these dampers the temperature in the upper portion of the structure around the retorts can be governed and controlled. In addition to the dampers 54 I provide a 60 damper 57 which is located in the passage between the two lower flues and by which the draft from the stack is regulated.

The essential feature of my invention is

the formation of the passages and flues located at the right and at the left of the firebox or heating apartment, the air entering at the base of the structure passing upwardly through passageways, then downwardly on the same side contacting with the sides of the flues then passing underneath 70 and up through ports on the opposite side again contacting with the heated flues and finding outlet into the combustion chamber; this air when mixed with the products of combustion creating an excessive heat and 75 then contacting with the several gas retorts is deflected downwardly and permitted to pass out through the flues excessively heating the air passing around the same.

The products of combustion which pass 80 through the center row of nostrils 58 located at the extreme top of the arch 17 is deflected to the right and left communicating with the combustion chambers 37 through a checker work of tiles 59 (see Fig. 1.)

85

Having fully described my invention what I claim is:

1. A gas generator comprising a heating compartment, gas retorts located above the heating compartment, a tier of flues for the 90 passage of the products of combustion built in the structure and located to the right and left of the heating compartment, the flues so constructed as to form air passages through which the air is permitted to pass up, then down, then under and up around the flues permitting the air to be excessively heated and ports through which said air is passed to be mixed with the products of combustion, substantially as specified.

100

2. A gas generator comprising a structure, a fire box mounted therein, retorts located above the fire box, a tier of flues located in the structure to the right and left of the fire box and located horizontally, a plurality of air passages formed in the structure on both sides of the flues, passages for admitting the air from the base of the structure passing upwardly then downwardly on one side, then under and up on the other side and fed 105 through a plurality of passages to intermingle with the products of combustion discharged from the fire box, combustion chambers for receiving the mixture of air and products of combustion and passages for permitting the unused heat to pass out by 110 way of the flues primarily and excessively heating the air circulating around the same, substantially as specified.

115

In testimony whereof, I have signed my 120 name to this specification, in presence of two subscribing witnesses.

WILLIAM C. LOUDON.
